UNITED STATES PATENT OFFICE.

ALLAN LEONARD MARSHALL, OF ST. JOHN, NEW BRUNSWICK, CANADA.

DESIGN FOR A KEYHOLE-FINDER.

42,639.

Specification for Design.

Patented June 18, 1912.

Application filed February 24, 1912. Serial No. 679,764. Term of patent 14 years.

To all whom it may concern:

Be it known that I, ALLAN LEONARD MARSHALL, a subject of the King of Great Britain, residing at St. John, in the Province of New Brunswick and Dominion of Canada, have invented a new, original, and ornamental Design for Keyhole-Finders, of which the following is a specification, reference being had to the accompanying drawing, forming part thereof.

The figure is a perspective view of a keyhole finder showing my new design.

I claim:

The ornamental design for a keyhole finder, as shown.

A. LEONARD MARSHALL.
